UNITED STATES PATENT OFFICE.

JACOB PFUND, OF LA CROSSE, WISCONSIN.

IMPROVEMENT IN CUSPADORES.

Specification forming part of Letters Patent No. 178,025, dated May 30, 1876; application filed April 20, 1876.

To all whom it may concern:

Be it known that I, JACOB PFUND, of La Crosse, in the county of La Crosse and State of Wisconsin, have invented certain new and useful Improvements in Spittoon, of which the following is a specification:

My invention relates to cuspadores; and it consists in the construction and arrangement of a base and a cuspadore removably placed in the same, as will be hereinafter more fully set forth.

In order to enable others skilled in the art to which my invention appertains to make and use the same, I will now proceed to describe its construction and operation, referring to the annexed drawings, which form a part of this specification, and in which—

Figure 1 is a side view. Fig. 2 is a vertical sectional view through the cuspadore and base.

A represents the base for my cuspadore, which base may be struck up of sheet metal, or otherwise formed of paper or any other suitable material. It is made in circular form, with its center raised, as shown, and its outer edge corrugated. Base A has no bottom, but rests upon the floor at its edges, where it may be provided with a rim, if desired. In the raised center of the base is a circular aperture, around which is a downwardly-projecting flange, a, as shown.

The cuspadore is formed of a cylindrical body, B, closed at the bottom, and provided at its upper edge with a flaring top or mouth,

C. The body B should be of such diameter as to fit snugly in the central aperture and flange of the base, and of such height relative to the base that when inserted therein the cuspadore will rest on the floor. When not necessary to clean the base the cuspadore can be lifted out of the same, taken out to be emptied and cleaned, and returned to its place again.

The cuspadore and base may be made perfectly plain, or more or less ornamented, as desired, according to the taste or fancy of the manufacturer and purchasers.

Having thus fully described my invention, what I claim as new, and desire to secure by Letters Patent, is—

1. The bottomless base A, raised in the center and provided with a central aperture, the flange a, or its equivalent, substantially as and for the purposes herein set forth.

2. A cuspadore formed of a cylindrical body, B, and flaring top or mouth C, in combination with a bottomless base, A, having a central aperture, through which the body is passed, and resting on the floor, substantially as herein set forth.

In testimony that I claim the foregoing as my own I affix my signature in presence of two witnesses.

JACOB PFUND.
